UNITED STATES PATENT OFFICE.

CHARLES B. DYER, OF INDIANAPOLIS, INDIANA.

DESIGN FOR AN EMBLEM, A BADGE, BROOCH, PIN, CUFF BUTTON, WATCH FOB, OR AN ARTICLE OF SIMILAR NATURE.

Application filed November 20, 1922. Serial No. 4,346. Term of patent 7 years.

To all whom it may concern:

Be it known that I, CHARLES B. DYER, a citizen of the United States, residing at Indianapolis, Marion County, State of Indiana, have invented a new, original, and ornamental Design for an Emblem, a Badge, a Brooch, a Pin, a Cuff Button, a Watch Fob, or an Article of Similar Nature, of which the following is a specification, refer-

ence being had to the accompanying drawing, forming a part hereof.

The figure is a plan view of the button or pin embodying the design.

I claim:

The ornamental design for an emblem, a badge, a brooch, a pin, a cuff button, a watch fob, or an article of similar nature, as shown.

CHARLES B. DYER,
